US00D686064S

(12) **United States Design Patent**
Garza

(10) **Patent No.:** **US D686,064 S**
(45) **Date of Patent:** **** Jul. 16, 2013**

(54) **CONTAINER**

(71) Applicant: **Dart Container Corporation**, Mason, MI (US)

(72) Inventor: **Dean Garza**, Williamston, MI (US)

(73) Assignee: **Dart Container Corporation**, Mason, MI (US)

(**) Term: **14 Years**

(21) Appl. No.: **29/439,526**

(22) Filed: **Dec. 12, 2012**

Related U.S. Application Data

(63) Continuation of application No. 29/398,405, filed on Jul. 29, 2011, now Pat. No. Des. 675,517.
